US0D1019596S

(12) **United States Design Patent** (10) **Patent No.:** **US D1,019,596 S**
(45) **Date of Patent:** **** Mar. 26, 2024**

(54) **PAIR OF WIRELESS EARPHONES**

(71) Applicant: **SCUD (FUJIAN) ELECTRONICS CO., LTD**, Fuzhou (CN)

(72) Inventors: **Kezhao Liao**, Fuzhou (CN); **Fanghai Xie**, Fuzhou (CN); **Lei Hou**, Fuzhou (CN); **Longqin Wang**, Fuzhou (CN)

(73) Assignee: **SCUD (FUJIAN) ELECTRONICS CO., LTD**, Fuzhou (CN)

(**) Term: **15 Years**

(21) Appl. No.: **29/818,080**

(22) Filed: **Dec. 21, 2021**

(30) **Foreign Application Priority Data**

Oct. 23, 2021 (CN) 202130695345.4

(51) LOC (14) Cl. **14-01**

(52) U.S. Cl.

USPC **D14/223; D14/206**

(57) **CLAIM**

The ornamental design for a pair of wireless earphones, as shown and described.

DESCRIPTION

FIG. 1 is a front elevation view of a wireless earphone, of a pair of wireless earphones, showing our new design; the wireless earphone is shown separately for ease of illustration;

FIG. 2 is a rear elevation view thereof;

FIG. 3 is a left side elevation view thereof;

FIG. 4 is a right side elevation view thereof;

FIG. 5 is a top view thereof;

FIG. 6 is a bottom view thereof;

FIG. 7 is a perspective view thereof;

FIG. 8 is another perspective view thereof;

FIG. 9 is a front elevation view of a wireless earphone, of a pair of wireless earphones showing our new design; the wireless earphone is shown separately for ease of illustration;

FIG. 10 is a rear elevation view thereof;

FIG. 11 is a left side elevation view thereof;

FIG. 12 is a right side elevation view thereof;

FIG. 13 is a top view thereof;

FIG. 14 is a bottom view thereof;

FIG. 15 is a perspective view thereof;

FIG. 16 is another perspective view thereof; and,

FIG. 17 is a perspective view of the pair of wireless earphones.
